CLAIM

The ornamental design for tire, as shown and described.

DESCRIPTION

FIG. 1 is a perspective view of tire showing our new design;
FIG. 2 is a front view thereof;
FIG. 3 is a back view thereof;
FIG. 4 is a left view thereof;
FIG. 5 is a right view thereof;
FIG. 6 is a top view thereof;
FIG. 7 is a bottom view thereof; and,
FIG. 8 is an enlarged view of the encircled area 8 of FIG. 2.
The broken lines shown on the drawings depict portions of
the tire that form no part of the claimed design.
